(57) **CLAIM**

The ornamental design for a tool for removal of material from tubular container, as shown and described.

DESCRIPTION

FIG. 1 is a top view of my tool for removal of material from tubular container, in accordance with my new design, the bottom being a mirror image thereof;

FIG. 2 is a left side view thereof, the right side view being a mirror image;

FIG. 3 is a rear view thereof;

FIG. 4 is a front view thereof;

FIG. 5 is a front perspective view thereof; and,

FIG. 6 is a front perspective view in a use condition.

Broken lines as shown are intended to show the environment of the design and do not form a part of the claimed design.
